UNITED STATES PATENT OFFICE.

FREDERICK BOGENBERGER, OF MILWAUKEE, WISCONSIN.

SASH-PIVOT.

No. 897,449.

Specification of Letters Patent.

Patented Sept. 1, 1908.

Application filed April 16, 1908. Serial No. 427,455.

To all whom it may concern:

Be it known that I, FREDERICK BOGENBERGER, a citizen of the United States, residing at Milwaukee, in the county of Milwaukee and State of Wisconsin, have invented certain new and useful Improvements in Sash-Pivots; and I do declare the following to be a full, clear, and exact description of the invention, such as will enable others skilled in the art to which it appertains to make and use the same.

This invention relates to sash pivots and particularly to an improved pivot or pivoting mechanism to be used in connection with fire-proof windows whose sashes and frames are made up of sheet metal.

The object of the invention is to provide a device of this character which is limited in its movement, and which closes automatically when released so as to cut off draft through the building.

Preferably these windows are held open by fusible links so that upon an excessive rise in temperature, due to a fire or other similar cause, they are released and swing into closed position automatically, and while I have not shown any means for holding the sash in open position, I wish it understood that I may use any automatic means for releasing the sash upon a predetermined rise in temperature, the universal means as hereinbefore stated being a fusible link.

A further object of the invention is the provision of means for adjusting the pivotal connection of the sash so that no manner of warping, expansion or contraction will hold the sash in open position when it is desired to have it closed.

Another object of the invention is to provide means whereby the limiting means above mentioned may be rendered inoperative so as to permit the window to be swung open to a greater degree for washing or any other purpose.

With these and other objects in view, the invention consists of certain novel features of construction, combination and arrangement of parts as will be described and particularly pointed out in the appended claims.

In the accompanying drawings, Figure 1 is a front elevation; Fig. 2 is a fragmentary front elevation, partly in section, and on an enlarged scale; Fig. 3 is a fragmentary vertical sectional view taken on line 3—3 of Fig. 2;

Fig. 4 is an enlarged detail sectional view of the pivot bolt and its associated parts; and Fig. 5 is a modification thereof.

Referring more particularly to the drawings, and especially to Fig. 1, where the sash is pivoted in the frame, I have indicated the sash by the numeral 1, and the frame by the numeral, 2. Both the sash and the frame are constructed in a similar manner and are made not with a view to their appearance, 60 but for fire-proof purposes. They are preferably constructed of a thin sheet of metal, 3, which is bolted to a heavy metallic backing, 4, by bolts, 5. The backing, 4, in the sash and in the frame serves as a body to which 70 the bracket-securing bolts are attached, as will be hereinafter described.

Secured to the frame, 2, is a supporting arm, 6, by bolts, 7, which pass through the enlarged apertures, 8, of the frame, 6, and 75 engage the backing, 4, of the frame. These apertures are made of a considerably larger internal diameter than the external diameter of the bolt so as to permit of adjustment at all times. As the arms and other connections with the sash are identical on both sides of the frame, I shall describe only one, and its associated parts. The arm 6 is bent outwardly as at 9, and is then provided with an upstanding projection, 10, apertured at 11 80 to receive the pivot bolt, 12, which passes through the bushed opening, 13, formed in the right-angular flange, 14, of the sash plate, 15. The bolt, 12, is threaded into the aperture, 11, so as to hold it stationary with respect to the arm, 6, so that the sash rotates upon the enlarged portion of the bolt which is within the bushed opening, 13. The flange, 14, is provided above the bolt, 12, and adjacent the body, 15, with a pivot pin, 16, 90 upon which is carried a limiting pawl, 17, having a weighted outer end, 18, and a thumb piece, 19, for raising the same. When the sash is tilted upon the pivotal bolt, 12, the pawl travels over the upper surface of the 100 arm, 6, until it engages the limiting stud, 20, formed upon the arm, which prevents any further movement of the sash. By pressing back on the thumb piece 19 of the pawl, the latter may be carried over the lug 20 so that 105 the frame may be tilted to any desired position for the purpose of washing the glass, or for any other purpose. The thumb piece is arranged so that the weighted end of the limiting pawl cannot be tilted past the center, 110

because the thumb piece engages the sash when pressed back and when released it will drop by gravity upon the upper surface of the arm 6. Unless held open by the fusible link 5 before mentioned, the sash will drop back to normal or closed position, owing to the fact that the sash plate, 15, and the pivot bolt are slightly above the horizontal center of the frame.

10 In the modification shown in Fig. 5, the frame 2 is provided with a bushed opening, 21, through which the smooth outer end, 22, of the bolt, 23, is adapted to pass, the bolt being held securely in the flange 14 by screw 15 threads, 24. These bushings around the openings are of brass, or other non-rusting material in order to conform to the regulations of the National Board of Fire Underwriters, which requires that hinge parts 20 of fire-proof windows be of non-corrosive metals.

From the foregoing description, taken in connection with the accompanying drawings, the construction and operation of the invention will be readily understood without requiring a more extended explanation.

25 Various changes in the form, proportion and the minor details of construction may be resorted to without departing from the principle or sacrificing any of the advantages of

the invention as defined in the appended claims.

Having thus described my invention, what I claim as new and desire to secure by Letters Patent, is:

35

1. A sash pivoting device comprising a sash plate member secured to the frame of the sash, a supporting member adjustably secured to the stile of the frame, a pivot bolt secured to one of said members and having 40 pivotal connection with the other member, a limiting stud on the supporting member, and a pawl carried by the sash supporting member adapted to engage said stud to determine the movement of the sash.

45

2. A sash pivoting device comprising a sash plate secured to the frame of the sash, an arm adjustably secured to the stile of the frame, a pivot bolt secured to the arm and having pivotal connection with the plate, a 50 limiting stud on the arm, and a pawl carried by the plate adapted to engage said stud to determine the movement of the sash.

55

In testimony whereof I have hereunto set my hand in presence of two subscribing witnesses.

FREDERICK BOGENBERGER.
